UNITED STATES PATENT OFFICE

2,533,615

WATER HEATER

Clark M. Osterheld, Stoughton, Wis., assignor to
McGraw Electric Company, Elgin, Ill., a corporation of Delaware

Application January 4, 1947, Serial No. 720,164

3 Claims. (Cl. 219—39)

1

My invention relates to electric heaters and particularly to electric water heaters.

An object of my invention is to provide a novel form of internal electric water heater.

Another object of my invention is to provide an internal electric water heater that shall comprise a novel form of electric insulation.

Other objects of my invention will either be apparent from a description of several forms of water heater embodying my invention or will be pointed out in the course of such description and set forth particularly in the appended claims.

In the drawings:

Figure 1 is a view in vertical section of a standard domestic hot water tank having associated therewith an electric water heater embodying my invention.

Fig. 2 is a fragmentary view in lateral section of an electric heater embodying my invention.

Fig. 3 is a view in lateral section taken on the line 3—3 of Fig. 2.

Fig. 4 is an end view of the heater shown in Fig. 1, taken on the line 4—4 of Fig. 1.

Fig. 5 is a fragmentary view, in side elevation with a part thereof in section, of a modified form.

Fig. 6 is an end view of the device of Fig. 5.

Fig. 7 is a fragmentary view of a still further modification, and,

Fig. 8 is an end view of the device of Fig. 7.

Referring first of all to Fig. 1 of the drawings, I have there shown a standard domestic hot water tank 11 having a lower closure member 13 which is provided with a cold water inlet pipe 15. I provide also an upper closure 17 which is provided with a hot water outlet pipe 19. I provide also a mass of heat insulation 21 such as mineral wool, which heat insulation is held in proper operative position around tank 11 by an outer casing 23.

An electric heater 25 embodying my invention comprises an outer tubular metallic member 27 having a closed inner end, which may be made of any suitable metal but is preferably made of relatively thin aluminum, the thickness of this aluminum, being on the order of .035". While I have given a preferred thickness I do not desire to be limited to this thickness but may make the thickness from .03" to .04". The tube 27 is preferably bent to zigzag form so as to comprise a plurality of substantially straight convolutions.

I provide a resistor 29 which resistor is wound to helical form of such dimensions that the outer portions of each turn shall engage the inner surface of tube 27. While I may use standard electric resistance wire I prefer to make the material

2

of resistor 29 of aluminum and while I have shown the resistor conductor as being substantially circular I may use any other shape of conductor in lateral section.

I cover the entire outer surface of resistor conductor 29 with an integral, inorganic, heat-conducting, high-temperature-resisting and electric-insulating coating, the thickness of this coating being on the order of .001" although the thickness may vary from .0005" to .0015".

While I have hereinbefore stated that only the conductor is covered with an electric-insulating coating I may also provide a similar coating on the aluminum tubular member 27 on both the 15 inside and the outside surfaces.

In forming the electric heater I insert the electrically wound conductor 29 in tube 27 and then bend the tube to substantially zigzag form, it being evident that there will be no short circuit occurring between adjacent turns at the point where they come close together as shown at 31 in Fig. 2 of the drawings.

I mount the outer end of tube 27 on a plate 33, which plate is adapted to be mounted against a plate 35 which may be secured against the outer convex surface of tank 11 as by a welded seam 37. I support the heater 25 on plate 33 as by a welded seam 39, it being understood that the shape of plates 33 and 35 are made such as to cooperate with each other to provide a watertight joint when secured against the outer surface of tank 11 over an opening 41 provided therein. The inner end of tube 27 is closed and the inner end of resistance conductor 27 is brought out at the front end thereof by a conductor 43 which conductor may be a part of conductor 29. An externally-threaded nut 45 is adapted to be screwed into plate 33 to hold the heater 25 in fixed and proper operative position within the tank. It is evident that the diameter or size of opening 41 must be such that bent tube 27 may be inserted into opening 41 and into tank 11.

I may hold heater 25 in proper operative watertight position against plate 35 as by a plurality of bolts 47, each having a nut 49 screwed thereon, bolts 47 being secured to plate 35.

Referring now to Figs. 5 and 6 of the drawings, I have there shown a modification of electric heater comprising a preferably aluminum tube 51 having a closed inner end and a thickness as hereinabove set forth in connection with tube 27 and having therein a resistance conductor 29. The only difference between the design shown in Figs. 5 and 6 and that shown in Figs. 1 to 4 inclusive is that tube 51 is wound to extended helical shape.

It is evident that tube 51 may be easily and quickly inserted in tank 11 through opening 41 by merely screwing in the helically wound tube 51 until the straight end portion 53 is positioned in opening 41 when it may be held in watertight engagement by means similar to that shown as applied to electric heater 25 in Figs. 1 and 2.

Referring now to Figs. 7 and 8, I have there shown another modification comprising a tube 55 which is bent to acute angles in zigzag form. 10 Although I have shown these angles connecting the zigzag portions as sharp it will be understood that it will probably be impossible to make them as sharp as shown in Fig. 7 of the drawings. Substantially the same comments as hereinbefore 15 made in connection with the heater construction shown in Figs. 1 and 2 apply also to the heaters shown in Figs. 5 and 6 as well as to those shown in Figs. 7 and 8.

Internal heaters of the kind heretofore used have been of substantially hairpin shape, comprising a tube enclosing a resistance conductor, which is bent to hairpin shape and while the plane of the hairpin will be substantially horizontal the amount of heat-transmitting surface provided thereby will not be anywhere nearly equal to the heat-transmitting surface of any one of the designs shown in Figs. 1, 5 and 7 of the drawings. Considerable trouble has been experienced with water containing lime, which lime is deposited 20 upon the relatively high-temperature surface of the electric heater and since my electric heater provides a much greater heat transmitting area the amount of lime, if any, deposited upon the 25 external surface of the heater tube will be much less.

This lesser amount of heat energy transferred per unit area of electric heater results in substantially perfect freedom of lime deposits, thereby by providing an electric heater which will operate 40 for extended periods of time before it becomes necessary to remove the heater and clean its external surface.

Various modifications may be made in the device embodying my invention without departing from the spirit and scope thereof and I desire that all such modifications coming clearly within the scope of the appended claims shall be considered a part of my invention.

I claim as my invention:

1. In combination in an immersion type electric heater for a water tank or the like, a sealing member adapted to be mounted on a tank for sealing an opening therein and for supporting a heat-

er in the tank, an elongated tubular casing having one end supported on and sealed to said sealing member and having the other end closed, said casing having lateral dimensions small enough to pass through a tank opening that said sealing member is adapted to close, said casing being convoluted in a screw shaped pattern that is wider than said opening whereby said convolute casing is much longer than the longer dimension of the space it occupies, and may be mounted in said tank by being threaded through said opening, and an electric resistor element in said casing extending substantially from said sealing member to said closed end.

2. In combination in an immersion type electric heater for a water tank or the like, a sealing member adapted to be mounted on the tank for sealing an opening therein and for supporting a heater in the tank through said opening, an elongated heating unit having one end fixed to said sealing member and supported thereon, said heating unit having lateral dimensions small enough to permit it to pass through the tank opening, and being convolute in a screw shaped pattern that is wider than said opening, whereby said convolute heater occupies a space, the longest dimension of which is much shorter than the developed length of the heater, and may be assembled to said tank by being threaded screw-like through said opening.

3. The combination of claim 1 wherein said tubular casing is substantially round in cross section, said electric resistor element comprises a wire formed in a helix that fits snug in said casing, and wherein said wire has on its entire surface, an integral, inorganic, heat-conducting, high-temperature-resisting, electric-insulating coating.
